UNITED STATES PATENT OFFICE.

GEORGE A. GALLOWAY, OF FOUNTAIN, INDIANA.

FENCE.

SPECIFICATION forming part of Letters Patent No. 350,127, dated October 5, 1886.

Application filed January 5, 1886. Serial No. 187,685. (No model.)

To all whom it may concern:

Be it known that I, GEORGE A. GALLOWAY, a citizen of the United States, residing at Fountain, in the county of Fountain and State of Indiana, have invented certain new and useful Improvements in Fences, of which the following is a specification, reference being had thereto to the accompanying drawings.

My invention relates to indestructible or fire-proof fences, my object being to construct a fence in sections of burned earthenware or clay, the sections being dovetailed together and braced, as will be hereinafter described.

In the accompanying drawings, making a part of this specification, Figure 1 represents a side elevation, and Fig. 2 a transverse section.

In the figures, A represents the base of the fence, which may be in either one or two pieces, and which has molded upon its upper face projections near its outer ends, which are so formed at their upper ends that they may engage sections of the fence, which, when joined, form a dovetailed connection.

B and B' represent two of the side sections of the fence, said fence being built in V or tapering shape, as represented, space being left between the two sides. Each end of the sections is formed or beveled and grooved, so that they readily dovetail together as one is placed upon the other.

C represents the cap-piece, which has two downwardly-projecting sides, the lower edges of which are formed in a manner similar to

that of the contiguous sections, so that they will fit and dovetail with them.

D represent braces, which are placed between the two sides of the fence, and which have their ends dovetailed into the sections B B'. These braces prevent both the separation and the collapsing of the sides.

All the parts of this fence are made of clay or other similar suitable material, and then burned or baked. When put together, it is fire-proof, will endure for ages, and can be constructed at a reasonable cost, certainly as compared with its advantages.

Having thus fully described this invention, what I claim as new, and desire to secure by Letters Patent, is—

1. The combination, with the base having dovetailed projections, of the side sections dovetailed to the base and to each other and inclining inwardly toward the top, and the conical cap dovetailed to and surmounting said sections, substantially as specified.

2. In combination with the dovetailed sections and base, constructed as described, the internal braces dovetailed thereto, substantially as specified.

In testimony whereof I affix my signature in presence of two witnesses.

GEORGE A. GALLOWAY.

Witnesses:

SAMUEL CLARK,

HARRISON J. REED.
